RAZOR BLADE AND HOLDER

William G. Adams, Richmond, Va.

Application April 13, 1931. Serial No. 529,815

17 Claims. (Cl. 30—12)

The invention relates to razors of the so-called safety type in which there is provided a blade clamped and flexed between coacting members.

It is well known that in razors of this type there is provided a body member and a cap between which the blade is interposed, the cap being commonly provided centrally with a threaded stud extending through a hole in the body and received within a threaded socket in a handle. Furthermore the cap is customarily provided either with studs or longitudinally extending ribs passing through holes or slots in the blade and body for the purpose of centering or positioning the blade properly so that the cutting edges thereof will be at the proper location with respect to the guards formed on the edges of the body to insure the proper cutting action. An objection to the present type of blade, which is initially flat throughout until flexed, is that it is difficult to pick up when laid upon the flat smooth top of a washstand, table or the like. Moreover as such an ordinary blade will contact throughout its area with the flat surface upon which it may be placed it will not dry off after washing as water will be confined between it and the supporting surface and the result is that the blade will rust.

It is with the above and other facts in view that I have devised the present invention which has for its general object the provision of a novel blade and holder therefor, the combination defining a razor having improved characteristics.

An important object of the invention is to provide a holder and blade having coacting means for centering or properly positioning the blade without reliance upon the usual studs provided for the purpose, the centering means being entirely independent or irrespective of such studs if they be present as they are in some but not all types of razors.

Another object of the invention is to provide a holder in which the ordinary blade cannot be employed, thereby making it necessary for the user to purchase the special blades which form part of the combination and, conversely, to provide a blade which cannot be used with the ordinary holders on the market but which requires one of special construction.

A very important object of the invention is to provide a blade having means thereon which will positively prevent it from lying flat upon a washstand or other surface, thereby insuring drying after washing and avoiding the rusting which would otherwise invariably occur unless the blade be made of some rust-proof material.

Still another object of the invention is to provide a razor blade in which the means for preventing it from lying flat will also serve as a finger-grip enabling it to be readily picked up and manipulated without danger of cutting the fingers or injury to cutting edges.

A more specific object of the invention is to provide the combination of a blade with projecting portions thereon for the purpose set forth, and a holder having means cooperating with said projections to effect proper positioning of the blade between the parts of the holder.

A further object is to provide a blade and holder combination in which the latter may embody a permanently pivotally or flexibly connected cap and body or a bodily detachable cap, it being possible in the first instance to have the blade carried by and movable with the cap or placed initially upon the body itself, whichever is preferred, the latter method being resorted to in the case of the second mentioned type of holder.

An additional object is to provide a construction and arrangement of this character which will be simple and inexpensive to make, easy to use, positive in action, efficient and durable in service, and a general improvement in the art.

To the attainment of the foregoing and other objects and advantages, the invention preferably consists in the details of construction and the arrangement and combination of parts to be hereinafter more fully described and claimed, and illustrated in the accompanying drawing in which:

Figure 1 is an end elevation of a holder of the hinged cap type showing it constructed for use with my novel blade.

Figure 2 is a plan view of the blade alone showing the preferred form thereof.

Figure 3 is an end view of the blade,

Figure 4 is a side elevation thereof,

Figure 5 is a plan view of a blade embodying a slight modification,

Figure 6 is an end view thereof,

Figure 7 is a side or edge view.

In carrying out the preferred form of the invention, I provide a blade 10 having longitudinal cutting edges 11 and a central hole 12 for the passage of the screw or threaded post which is ordinarily carried by the cap of the holder. The blade is also shown as formed with other holes 13 which are for the accommodation or passage of the studs which project from the cap in some types of holders. Even if the holder be unprovided with such studs the holes 13 as well as the

95

100

110

hole 12 will operate to reduce the stiffness of the central portion of the blade so that it may flex more readily. In Figure 2 the ends of the blade are shown as curved but it will be understood 5 that this is merely a matter of design and not any material feature.

The outstanding characteristic of the blade shown in Figures 2, 3 and 4 is the provision at both ends thereof of means which will prevent 10 it from lying flat upon any surface and which will also serve as a finger grip to facilitate handling. This means comprises lugs 14 arranged in pairs and projecting from the blade, the lugs at one end projecting from one side and those at 15 the other end projecting from the opposite side. These lugs may be very simply formed by slitting the ends of the blade along inclined or diagonal lines 15 and then bending or striking out the material between these lines and other lines 20 16 which extend longitudinally of the blade between the inner ends of the slits 15 and the ends of the blade. The lugs 14 are consequently triangular in shape. Single lugs could be used.

As a modification, I may provide the blade 17 shown in Figures 5, 6 and 7, this modified blade having longitudinal cutting edges 18, a central hole 19, and other holes 20 at opposite sides of the central hole. This form of blade differs from the form above described in that the pairs of lugs 25 21 which project from the blade are differently defined. These lugs may be formed simply by slitting the end portions of the blade at the longitudinal center line, making transverse cuts 22 and then striking out the material. The lugs 21 25 of course extend longitudinally and are in spaced parallel relation with one pair projecting from one side of the blade and the other pair projecting from the opposite side. The difference between this arrangement and the one first described is that in the second form there is no metal between the lugs and they are of rectangular shape. However, both forms will operate or will be capable of use in identically the same manner.

Clearly, a blade constructed in either of the two alternative ways disclosed thus far could not be used with an ordinary holder as it is obviously necessary to modify the latter in order to accommodate the lugs 14 or 21. It is one of the objects 50 of the invention to provide a razor or holder and blade combination in which the holder may be formed as disclosed in my co-pending application for patent for Safety razors, filed March 25, 1931, Serial No. 525,274. While said application will naturally speak for itself, it might be well for the sake of clearness to mention at this point that the razor disclosed therein, or at least one form thereof, embodies a body with a cap connected thereto by means of spring pressed arms. In order that the present application may stand entirely upon its own feet I have, in Figure 1, illustrated a holder constructed as in said copending application. Referring to this figure the numeral 23 designates the body or guard to each end of which is pivoted, at 24, a link 25 to which is pivoted at 26 the cap 27 which is provided centrally with a threaded post or screw 28 adapted to pass through a hole in the body or guard and to be received within a threaded socket in the 70 handle 29 which is swivelly connected with the underside of the body or guard. The arms 25 are pressed upwardly by leaf springs 30 which are anchored at one end to the body and at the other end to the arms, the purpose being to maintain 75 the arms and consequently the cap in elevated po-

sition or in spaced relation to the body when the handle 29 is rotated to effect disengagement of the threaded post or screw 28. The purpose of maintaining this spaced relation to the cap is to permit it to be swung back or into open position without danger of the edge of the blade engaging against the body, it being a feature that the blade will remain in position against the cap owing to its engagement with the threads in the post.

In order that the blade shown in Figure 2 or Figure 5 may be employed in a holder of this type, I form the arms 25 and cap 27 with notches 31 and 32, respectively, which will receive the lugs 14 or 21 and which will therefore operate to center or position the blade properly with respect to the body 23 and cap 27. Of course the hole 12 or 19 will accommodate the threaded post 28. The usual centering posts are not provided in a holder constructed as shown in Figure 1 and the holes 13 therefore are idle though of course they exercise their function of rendering the intermediate portion of the blade more flexible. As the lugs 14 or 21, as the case may be, are preferably of greater length than the thickness of the arms 25 the end portions of the body or guard 23 are disclosed as similarly notched as at 33, the notches 31 and 33 registering when the arms 25 and cap 27 are drawn down into clamping position with the blade interposed between the cap and the arms and body. It might be mentioned that if the arms 25 are relatively wide or thick and the lugs 14 or 21 comparatively short it will not be necessary to provide the notches 33 as they may be provided only in the arms 25. It will be observed that while each arm and each end of the cap is shown as provided with a relatively long or wide notch it is just as feasible to provide two separate notches for the reception of the individual lugs 14 or 21, if such be preferred for any reason.

In the use of my blade in connection with the type of holder shown in Figure 1 it will be apparent that it is optional with the user whether he engages the blade upon the threaded post 28 when the cap is in released and open position as shown or lays it in position upon the body and arms. In fact the second mentioned procedure is preferable as there will then be no possibility of accidental slipping or derangement of the parts though if the lugs 14 or 21 be long enough they will engage within the notch 32 at one end or the other of the cap. The blade having been placed in position at either location preferred, the cap 27 is swung down so that the post 28 will be in alignment with the socket in the handle 29. Slight pressure is then applied to the cap while the handle is rotated to draw the threaded post into the threaded socket and the cap is thus brought into clamping relation to the blade. The lugs 14 or 21 at one end of the blade will be accommodated within the notch 32 in one end of the cap while the lugs at the other end of the blade will be received within the notch 31 in one arm and in the notch 33 in the corresponding end of the body, if the notch 33 is found to be necessary. Clearly the blade cannot shift in any position owing to the cooperative relation between the lugs and notches.

In view of the fact that the blade is flexible and is bowed into concavo-convex form when it is clamped between the parts of the holder, it is to be readily seen that the lugs 14 or 21, as the case may be, will be caused to diverge at the convex side of the blade and to converge at the concave side. This is a great advantage inasmuch as

when the pairs of lugs are engaged within the recesses provided for their reception in the holder parts the lugs on the convex side having a tendency to diverge will engage frictionally against the walls of the recess within which they are accommodated. If spaced recesses were to be provided for the reception of the lugs those at the concave side would grip against the walls of the recesses. Naturally this greatly increases the holding action and still more positively insures proper positioning.

My novel blade is not limited to use in connection with a holder such as that shown in my co-pending application and in Figure 1 of the drawing as it is capable of employment in association with a holder of a common or conventional pattern though necessarily modified to a certain extent which will be explained. Furthermore the precise lug arrangement or formation shown in Figures 2 and 5 is not the only plan that can be followed as I may resort to other conceivable variations.

From the foregoing description and a study of the drawing it will be apparent that I have thus provided a very simple arrangement and construction and combination of holder and blade which will adequately perform all the functions for which it is intended. It is believed that from the foregoing the construction, operation and advantages will be readily apparent to one skilled in the art without further explanation.

While I have shown and described the preferred embodiments of the invention, it should be understood that the disclosure is merely an exemplification of the principles involved as the right is reserved to make all such changes in the details of construction as will widen the field of utility and increase the adaptability of the device provided such changes constitute no departure from the spirit of the invention or the scope of the claims hereunto appended.

Having thus described the invention, I claim:

1. In combination, a razor structure comprising a holder embodying relatively movable parts, and a normally flat flexible blade interposed between said parts and adapted to be flexed by said parts, the parts of the holder being formed in their ends with recesses and the blade having pairs of integral projections fitting within said recesses to effect positioning with respect to the holder and to prevent displacement of the blade in any direction.

2. In combination, a razor structure comprising a holder embodying relatively movable parts and a flexible blade interposed between said parts, and flexed thereby when in operative position for shaving the parts of the holder being formed at their ends in their confronting faces with recesses and the blade having pairs of flexible projections at its ends fitting within said recesses to effect positioning with respect to the holder and to prevent displacement of the blade in any direction, the projections having their edges abutting against the walls of the recesses.

3. In combination, a razor structure comprising a holder embodying relatively movable parts and a blade adapted to be interposed between said parts and to be flexed thereby, the parts of the holder being formed at their ends, between the corners, with recesses and the blade having pairs of integral flexible projections fitting within said recesses to effect positioning with respect to the holder and to constitute sole means for preventing displacement of the blade in any direction, the projections being located at the ends of

the blade and each pair projecting from an opposite side thereof.

4. In combination, a razor structure comprising a holder embodying movably connected parts and guide means thereon and a flexible initially flat blade interposed between said parts and adapted to be flexed thereby, the parts of the holder being formed with recesses and the blade having openings receiving said guide means for preliminarily positioning the blade and pairs of projections extending longitudinally of the blade fitting within said recesses to effect final positioning with respect to the holder and to prevent displacement of the blade in any direction, the projections being formed as lugs struck out from the material of the blade, the projections being located at the ends and projecting laterally from opposite sides of the blade at the respective ends thereof.

5. In combination, a razor structure comprising a holder embodying movably connected parts and a flexible blade interposed between said parts, the parts of the holder being provided with guide studs and formed with recesses and the blade having openings receiving the studs for effecting preliminary positioning and being provided with pairs of flexible projections fitting within said recesses to effect positioning with respect to the holder irrespective of the studs and openings and to prevent displacement of the blade in any direction, the projections extending from the opposite sides of the blade to prevent the same from lying flat upon a supporting surface and thereby maintain the blade edges out of contact with such surface.

6. In combination, a razor structure comprising a holder embodying movably connected parts and a flexible blade interposed between said parts, the parts of the holder cooperating to flex the blade and being formed with recesses extending inwardly from the ends and the blade having pairs of projections at its ends fitting within said recesses to effect positioning with respect to the holder and to prevent displacement of the blade in any direction, the pairs of projections extending from the opposite sides of the blade to prevent the same from lying flat upon a supporting surface and further serving as finger grips to facilitate picking up the blade from a supporting surface.

7. In combination with a holder formed of movably connected parts formed at their ends with recesses, a blade adapted to be flexed by said parts provided at its ends with lugs fitting within said recesses for positioning the blade with respect to the holder, the lugs at each end being arranged in pairs projecting in the same direction and the pairs at the respective ends projecting from opposite sides of the blade, the pair at the convex side of the flexed blade spreading apart to grip the side walls of the recess.

8. In combination with a holder formed of movably connected parts formed at their ends with recesses, a flexible blade adapted to be flexed by said parts provided at its ends with lugs fitting within said recesses for positioning the blade with respect to the holder, the lugs at each end being arranged in pairs projecting in the same direction and the pairs at the respective ends projecting from opposite sides of the blade, each pair of projections serving to prevent the blade from lying flat and also constituting finger grips for facilitating handling, the pairs at the convex and concave sides of the flexed blade moving

ing outwardly and inwardly respectively when the blade is flexed.

9. In combination with a holder formed of movably connected parts formed at their ends with recesses, a flexible blade provided at its ends with lugs fitting within said recesses for positioning the blade with respect to the holder, the lugs at each end being arranged in pairs projecting in the same direction and the pairs at the respective ends projecting from opposite sides of the blade, each pair of projections serving to prevent the blade from lying flat and also constituting finger grips for facilitating handling, all of said projections being formed as outstruck lugs and those at one side of the blade diverging and those at the other side converging when the blade is flexed.

10. In combination with a holder formed of movably connected parts formed at their ends with recesses, a flexible blade provided at its ends with lugs fitting within said recesses and constituting the sole means for positioning the blade with respect to the holder, the lugs at each end being arranged in pairs projecting in the same direction and the pairs at the respective ends projecting from opposite sides of the blade, each pair of projections serving to prevent the blade from lying flat and also constituting finger grips for facilitating handling, all of said projections being formed as outstruck lugs located at opposite sides of the longitudinal medial line of the blade, and one pair spreading outwardly for gripping the sides of the recess when the blade is flexed.

11. In combination with a holder formed of movably connected parts formed at their ends with outwardly flaring recesses, a blade provided at its ends with pairs of lugs fitting within said recesses with their edges abutting opposite walls thereof for positioning the blade with respect to the holder, the lugs at each end projecting in the same direction and the pairs at the respective ends projecting from opposite sides of the blade, each pair of projections serving to prevent the blade from lying flat and also constituting finger grips for facilitating handling, all of said projections being formed as outstruck lugs located at opposite sides of the longitudinal medial line of the blade, said lugs being of triangular shape with their wider ends outermost.

12. In combination, a razor structure comprising a holder embodying movably connected parts and a flexible initially and normally flat blade interposed between said parts to be flexed thereby when in shaving position, the parts of the holder being formed at the ends with recesses

and the blade having pairs of spaced projections at its ends fitting within said recesses to effect positioning with respect to the holder and to prevent displacement of the blade in any direction, the material of the blade being cut away inwardly from the ends at the sides of the projections to counteract the stiffening effect thereof.

13. A flexible razor blade provided at its ends with pairs of laterally deflected lugs, the lugs at the respective ends extending in opposite directions, the pair at the convex side of the blade when the blade is flexed spreading apart and being adapted to grip against recess walls in a holder.

14. A razor blade provided at its ends with laterally extending lugs, the lugs being arranged in pairs and those at the respective ends projecting from opposite sides of the blade, there being openings between the lugs extending clear to the ends.

15. A razor blade provided at its ends with laterally extending lugs, the lugs being arranged in pairs and those at the respective ends projecting from opposite sides of the blade, the lugs being struck out from the material of the blade and being of triangular shape with their wider ends outermost and adapted to have their edges abut against the bottom of recesses in a holder and to have their outer sides frictionally engage the side walls of such recesses.

16. A thin flexible razor blade adapted to be flexed between razor parts when in shaving position, said blade being formed with a pair of outstanding spaced lugs, the distance between the ends of said lugs, or the angle lying between them, tending to change as the curvature of the blade changes during flexing of the blade between razor parts, said lugs being adapted to cooperate with the razor parts for effecting relative positioning of the blade with respect to the razor parts.

17. A razor blade of the thin flexible double edged type provided between its center and each end with a pair of outstruck lugs, the lugs of each pair being located at opposite sides of the longitudinal center line of the blade, one pair of lugs projecting beyond one side only of the blade and the other pair projecting only beyond the opposite side, said lugs being adapted to cooperate with razor parts for effecting positioning of the blade with respect thereto, also serving as finger grips and additionally constituting means for preventing contact of the cutting edges of the blade with a surface upon which it may be laid.

130 WILLIAM G. ADAMS.
